UNITED STATES PATENT OFFICE.

JOSEPH KAUFMANN, OF PITTSBURGH, PENNSYLVANIA.

GARMENT POCKET.

Application filed September 18, 1922. Serial No. 588,816.

To all whom it may concern:

Be it known that I, JOSEPH KAUFMANN, a citizen of the United States, residing at Pittsburgh, in the county of Allegheny and 5 State of Pennsylvania, have invented certain new and useful Improvements in Garment Pockets, of which the following is a specification.

This invention relates to garment pockets, 10 and the object of the invention is to provide the ordinary inside pocket of a coat with two additional compartments from which matter can not be surreptitiously removed.

The application of my improved pocket is 15 illustrated and described in connection with a coat. It will be obvious that the same may be successfully used in other garments.

Another object of the invention is to provide a novel pocket for various kinds of 20 garments, the pocket having a number of safety compartments in which valuables can be carried and retained out of the reach of pick-pockets or persons that might otherwise remove the contents of an ordinary 25 pocket.

These and such other objects as may hereinafter appear are attained by a pocket of a novel construction that will be presently described in detail, and pointed out in the 30 appended claim and reference will then be had to the drawing forming a part of this specification, wherein there is illustrated a preferred embodiment of my invention. But it is to be understood that the construction 35 of the pocket can be varied without departing from the scope of the invention.

In the drawing forming a part of this specification:—

Figure 1 is a perspective view of a coat 40 turned inside out and embodying a pocket in accordance with my invention.

Figure 2 is an enlarged detail view thereof, with portions of the garment broken away.

Figure 3 is a vertical sectional view of the 45 garment pocket.

Figure 4 is a front elevation of the rear partition of the pocket.

In the accompanying drawing, 1 designates a coat of the ordinary construction 50 provided with an inside pocket 2 in accordance with my invention. The pocket 2 comprises a strip of fabric forming the back 3 of the pocket and a fabric strip forming 55 the front wall 4. A front and a rear partition 5 and 6, respectively, are arranged in

parallelism and positioned between the rear and front walls, 3, 4. The partition 6 is of greater length than the partition 5 and extends above the latter and has its upper 60 end interposed between and secured to the upper terminal of said walls 3, 4. The partition 5 is adjacent to the front wall 4 and the partition 6 is adjacent to the rear wall 3. A front compartment 7 is formed by the front wall 4 and the partition 5; an intermediate compartment 8 is formed by the partitions 5 and 6; and a rear compartment 9 is formed by the partition 6 and the rear wall 3. 65

The lower ends of the front and rear walls 4, 3, and side edges of the partitions 5, 6, are closed by being secured together, as indicated at 10.

Access is had to the front compartment 75 through the transverse entrance opening 11 in the front wall 4 which is constructed in the well known manner. The partition 5 is detached at its upper end to provide an entrance 15 to the intermediate compartment 80 8, and extends upwardly above the opening 11 and is overlapped by a flap 12 constituting that portion of the front wall 4 above the opening 11. The inner face of the flap 12 and the front face of the partition 5 are 85 preferably provided with respective interengaging portions of a snap fastener 12, but any other desired fastening means may be employed.

The partition 6 is connected at its upper 90 end together with the upper ends of the rear and front walls 3, 4, as indicated at 13, and is provided with a vertically extending centrally disposed slit 14 which extends throughout the entire length of the partition 6 and constitutes the entrance opening 95 for the rear compartment 9.

To obtain matter carried in the rear compartment 9 it would be necessary to pass 100 through the entrance 11 in the front wall 4, detach the fastener 12 permitting access to the intermediate compartment 8 through its entrance 15, and finally through the slotted entrance 14 of the partition 6 to the rear compartment 9. It will be noted that 105 matter carried in the latter would be concealed and inaccessible to persons that might otherwise remove the contents of an ordinary pocket.

What I claim is:—

110 A garment pocket comprising a front wall, a rear wall having its upper terminal

secured to said front wall, front and rear parallel partitions arranged between and forming in connection with said walls, front, intermediate and rear compartments, said
5 rear partition of greater length than and projecting above said front partition and having its upper end secured between said walls, said front wall extending above and over the upper end of the front partition,
10 the lower end and side edges of said rear wall and partitions secured to said front fall, inter-engaging means carried by the

front wall and front partition for detachably connecting the upper end of said partition to the front wall, said front wall having a transverse opening positioned below said means forming an entrance for the pocket and said rear partition having a lengthwise slit disposed medially thereof to provide an entrance for the rear compartment. 15 20

In testimony whereof I affix my signature.

JOSEPH KAUFMANN.
